UNITED STATES PATENT OFFICE

ALBERT SEBEK, OF CICERO, ILLINOIS, ASSIGNOR TO KRONE-SEBEK DIE CASTING & MFG. CO., OF CHICAGO, ILLINOIS, A CORPORATION OF ILLINOIS

DESIGN FOR AN AUTOMOBILE RADIATOR CAP

Application filed February 25, 1929. Serial No. 30,205. Term of patent 3½ years.

To all whom it may concern:

Be it known that I, ALBERT SEBEK, a citizen of the United States, residing at 2303 South 62nd Avenue, in the town of Cicero, county of Cook, and State of Illinois, have invented a new, original, and ornamental Design for an Automobile Radiator Cap, of which the following is a specification, reference being had to the accompanying drawing, forming part thereof.

Fig. 1 is a plan of an automobile radiator cap, showing my new design. Figs. 2 and 3 show the cap in side and front elevations, respectively. Fig. 4, is a rear view showing the ornamentation on the rear side of the cap body portion.

I claim:

The ornamental design for an automobile radiator cap as shown.

ALBERT SEBEK.
